John W. Matthews.

THE COLUMBIA PLANOGRAPH CO., WASHINGTON, D. C.

UNITED STATES PATENT OFFICE.

JOHN W. MATTHEWS, OF DIFFICULT, TENNESSEE.

RAILROAD-CROSSING DEVICE.

1,171,621.

Specification of Letters Patent. Patented Feb. 15, 1916.

Application filed May 26, 1915. Serial No. 30,640.

To all whom it may concern:

Be it known that I, JOHN W. MATTHEWS, a citizen of the United States, residing at Difficult, in the county of Smith and State 5 of Tennessee, have invented a new and useful Railroad-Crossing Device, of which the following is a specification.

The device forming the subject matter 10 of this application is adapted to be employed for automatically rendering continuous, in advance of an approaching train, the track upon which the train is traveling, the device being adapted to be used where a pair of tracks intersect.

15 The invention aims to provide novel means for rendering tracks continuous at the point of crossing, and to provide a novel wheel actuated mechanism whereby movable rail sections located at the points 20 where the tracks cross, may be shifted.

It is within the province of the disclosure to improve generally and to enhance the utility of devices of that type to which the present invention appertains.

25 With the above and other objects in view which will appear as the description proceeds, the invention resides in the combination and arrangement of parts, and in the details of construction hereinafter described.

30 and claimed, it being understood that changes in the precise embodiment of the invention herein disclosed can be made within the scope of what is claimed without departing from the spirit of the invention.

35 In the accompanying drawing: Figure 1 shows the device in top plan. Fig. 2 shows a vertical section of one base member, a vertical section of one rotatable member and a gap in railroad. Fig. 3, the lever mechanism. Fig. 4, a portion of right-angled-crank arm with roller, clevis and nut. Fig. 5, the capsule-compression-spring-mechanism, and Fig. 6, the compression-spring-mechanism.

40 45 In the accompanying drawings, is shown a pair of intersecting tracks indicated respectively by reference characters A and B, it being understood that the tracks A and B may intersect at any oblique angle. The 50 track A comprises rails 1 and 2, the track B comprising rails 3 and 4. A guard rail 5 extends between the rotatable members 14 and 18, and adjacent the track rail, a guard rail 20 extends from the rotatable 55 member 14 toward the lever mechanism and adjacent the track rail.

Located at the angle defined by the rails 1 and 3 is a base 7 having a lower recess 8, an intermediate recess 9, an upper recess 10 of successively increasing diameters as will 60 be evident from Fig. 2. A rotatable member 14 is carried by the base 7, the rotatable member being supported on a shaft 15 assembled with the base 7. For the lubrication of the rotatable member 14, an oil hole is 65 provided, the same being closed by a cap 17.

The rotatable member 14 comprises a body 23 conforming to the recess 8, a shoulder 24 conforming to the recess 9, and a flange 25 conforming to the rim of base 7 70 and the gap or recess 10 in the projection of the base 7. Interposed between the rotatable member 14 and the base 7 are anti-friction devices such as balls 18. In the projection of the base 7 are formed grooves 75 26 receiving the track rail and the guard rail 20, a second groove 26, on the projection of the base 7, being adapted to receive the corresponding track rail and the guard rail 5 which extends between the rotatable members 14 and 13. The rails 1—20 and 1—5 do not extend across the rotatable member 14 but terminate adjacent its periphery.

The rotatable member 14 is provided with 85 a groove 16 receiving rail sections 6 and a, located side by side. The rotatable member 14 is equipped as shown in Fig. 1 with pivots 19 for connecting with rods 69 and 70, with pivots 22 for connecting with chains 52, and with pivot 46 for connecting with the capsule-compression-spring mechanism. A sleeve 29, shown in detail in Fig. 5 is pivoted at 46 to rotatable member 14, and slides within a sleeve 28. Interposed 90 between one end of the sleeve 29 and a partition in the sleeve 28 is a compression-spring 30. The sleeve 34 is threaded on to a stem 32, and pivoted at 35 to a fixed support 27. Intermediate its ends, the stem 32 is provided with wrench receiving shoulders 33 whereby the stem 32 may be rotated in the sleeve 34 thereby securing an adjustment of the spring 30. It will now be understood that the structure shown in Fig. 105 5 constitutes a capsule-compression-spring-mechanism which stands obliquely against pivot 46, and in opposition to the compression-spring-mechanism herein after described.

Projecting from the rotatable member 14 is an arm 44 adapted to coact successively with compression-springs 43 110

mounted in sockets 41 and held therein by securing elements 42, the socket terminating in a stem 39 threaded as shown at 38 into a support 37. The stem 39 is provided with 5 wrench receiving shoulders 40 whereby the stem may be rotated in the support 37 thereby securing an adjustment of the compression-spring 43.

When the rotatable member 14 is turned 10 in one direction or the other, one of the springs 43 is put under compression, to serve as a resilient buffer on the adjustable stop 38. While the springs 30 are intended to be sufficiently strong to overcome any tendency which springs 43 might have to 15 rotate the rotatable members 13 and 14, the operation of the flange of a second car wheel, a third car wheel and so on, on the lever mechanism, in conjunction with the capsule-compression-spring-mechanism, would 20 tend to reconcile the rotatable members to the desired position, should springs 43 be sufficiently strong to rotate the rotatable members after the operation of the lever mechanism by the flange of the first car 25 wheel.

Coacting with the rails 2 and 4 is a rotatable member 14 of the sort hereinbefore described and mounted as hereinbefore mentioned, the rotatable member carrying rail sections 6 and *a*. A rotatable member 13 co-operates with the rails 2 and 3 and is constructed and mounted like the rotatable member 14, saving for the fact that two 30 pivots 22 and 22, two pivots 19 and 19 and one pivot 46 may be omitted, and one rail section 6 is added. The rotatable member 13 carries rail sections 6—*a*—6.

A rotatable member 13, constructed like 40 the first rotatable member 13 mentioned, co-operates with rails 1 and 4 and carries section-rails 6—*a*—6. At the angle defined by the rails 1 and 3, the rail section *a*, on the rotatable member, is adapted to co-operate 45 with the rail 1 or with the rail 3 and the rail section 6 co-operates with the guard rails 5 and 20. At the angle defined by the rails 2 and 4, the rail sections 6, on the rotatable member, is adapted to co-operate 50 with the guard rails 5 and 20, the rail section *a* co-operating with the rail 2 or with the rail 4. At the angle defined by the rails 1 and 4, the rail section *a*, on the rotatable member, co-operates with the rail 1 or with 55 the rail 4, and the rail section 6 co-operates with the guard rails 5. At the angle defined by the rails 2 and 3, the rail section *a*, on the rotatable member, co-operates with the rail 2 or with the rail 3, and the rail sections 6 co-operate with the guard rail 5'. 60

Connections in the form of rods 70 and 70 extends between the rotatable members 14 and 14 and are pivoted at their ends thereto. A connection in the form of a 65 rod 69 is pivotally united with the rota-

table member 14 and is pivotally united with the rotatable member 13 located respectively at the angles defined by the rails 1 and 3, 1 and 4. A connection in the form of a rod 69 is pivotally united with the rotatable member 14 and is pivotally united with the rotatable member 13, located respectively at the angles defined by the rails 2 and 4, 1 and 4. A connection in the form of a rod 69 is pivotally united with the rotatable member 14 and is pivotally united with the rotatable member 13, located respectively at the angles defined by the rails 2 and 4, 2 and 3. A connection in the form of a rod 69 is pivotally united with the rotatable member 14 and is pivotally united with the rotatable member 13, located respectively at the angles defined by the rails 1 and 3, 2 and 3. A fixed support 47 is provided and upon this support is mounted to swing a lever 46 comprising arms 49, 50 and 51. A spring 53 forms a connection between the arm 49 and a fixed anchor 54. A flexible element such as a chain 52 connects the arm 50 with the rotatable member 14. Pivotally connected with the arm 51 of the lever 46 is a connection in the form of a rod 55 extending parallel to the rail 1.

A lever mechanism is provided for operating the connection 55, and this portion of the structure is shown in detail in Fig. 3, wherein it will be observed that the connection 55 is pivotally united with a crank arm 56, upstanding, from one end of a shaft 57 journaled in bearings 58. The shaft extends transversely of the rail 1 and is provided with a socket in which is mounted to slide for adjustment, an arm 59 held in place by a set screw.

The arm 59 is right-angled at 61 carrying a clevis 65 and a roller 64. A wheel engaging lever 62 extends longitudinally of the rail 1 and rests on the roller 64 within the contour of the clevis 65, the lever being supported on a shaft 63 carried by bearings 66. Intermediate its ends, the lever 62 is arched upwardly as shown at 71, so as to extend above the rail 1 and to the side of rail and on the inside of the track, and to lie in the path of the flange of a wheel of a passing railway vehicle. At one end, the lever 62 carries a counter-weight 72. Disposed adjacent the rail 3 is a wheel actuated mechanism, adjacent the rail 2 is a wheel actuated mechanism, and an actuating mechanism is located adjacent the rail 4. The actuating mechanisms adjacent the rails 3, 2 and 4 need not be described in detail, since they are duplicates of the lever mechanism shown in Fig. 3.

Presupposing that a train is approaching the crossing on track A, a wheel of the locomotive rides onto the arched lever 62 and tilts the same on its fulcrum 63, and the

lever 62, coacting with the roller 64 rotates the shaft 57 through the medium of the arm 59, it being noted that the throw may be adjusted by moving the arm 59 in the 5 socket. From the shaft 57, motion is transmitted to the connection 55 through the arm 56. The connection 55 tilts the lever 48 by means of the arm 51, and the arm 50 of the lever 48, through the means of the chain 10 52 rotates the rotatable member 14 on the shaft 15. When the rotatable member 14 is rotated in the manner hereinbefore described, the rail section *a* is moved out of alinement with the rail 3 and is moved into 15 alinement with the rail 1, the rail section 6 moving out of alinement with the guard rails 5 and 20, adjacent the rail 3, and into alinement with the guard rails 5 and 20, of rail 1. From the rotatable member 14, motion 20 is transmitted to a second rotatable member 14 by way of the connections 70 and 70, the rail section *a* moving out of alinement with the rail 4 and into alinement with the rail 2, the rail section 6 moving 25 out of alinement with the guard rails 5 and 20 adjacent rail 4, and into alinement with the guard rails 5 and 20 adjacent rail 2. From the rotatable members 14 and 14, motion 30 is transmitted to the rotatable member 13 located at the angle defined by the rails 1 and 4, through the elements 69 and 69, the rail section *a* moving out of alinement with the rail 4 and into alinement with the rail 1, and a rail section 6 moving out of 35 alinement with the guard rail 5 adjacent rail 4; and, a section rail 6, on the opposite side of section rail *a* moving into alinement with the guard rail 5 of rail 1. From the rotatable members 14 and 14, motion is 40 transmitted to the rotatable member 13 located at the angle defined by the rails 2 and 3, through the connections 69 and 69, the rail section *a* moving out of alinement with the rail 3 and into alinement with the rail 2, and the rail section 6 moving out of 45 alinement with the guard rail 5, adjacent rail 3; and, the rail section 6, on the opposite side of the section rail *a*, moving into alinement with the guard rail 5, adjacent 50 rail 2. Thus it will be seen that when a train approaches the crossing, the crossing will be set in advance of the train, to afford a continuous track. The above operation, described, takes place in connection with 55 all of the four track branches shown in Fig. 1, when a train approaches the crossing on any of the said branches.

Having thus described the invention, I claim:—

60 1. In a device of the class described, a pair of intersecting tracks comprising rails; a rotatable member journaled at the angle defined by the rails; a rail section carried by the rotatable member and adapted to be 65 alined with the respective rails when the

rotatable member is operated; operating means for rotating the rotatable member; an arm projecting from the rotatable member; and opposed springs with which the arm successively coacts, the springs constituting a resilient buffeting mechanism for the rotatable member, substantially as described. 70

2. In a device of the class described, a pair of intersecting tracks comprising rails; 75 a rotatable member journaled at the angle defined by the rails; a rail section carried by the rotatable member and adapted to be alined with the respective rails when the rotatable member is operated; operating means for rotating the rotatable member; and opposed springs coacting with the rotatable member, the springs constituting a resilient buffeting mechanism for the rotatable member; and means for adjusting the 80 springs, substantially as described. 85

3. In a device of the class described, a pair of intersecting tracks comprising rails; 90 a rotatable member journaled at the angle defined by the rails; a rail section carried by the rotatable member and adapted to be alined with the respective rails when the rotatable member is operated; operating means for rotating the rotatable member; an arm projecting from the rotatable member; and opposed springs with which the arm successively coacts, the springs constituting a resilient buffeting mechanism for the rotatable member; and means for adjusting the 95 springs, substantially as described. 100

4. In a device of the class described, a pair of intersecting tracks comprising rails; a base located at the angle defined by the rails; a rotatable member journaled on the 105 base; a rail section carried by the rotatable member and adapted to be alined with the respective rails when the rotatable member is operated; operating means for rotating the rotatable member; an arm projecting 110 from the rotatable member; and opposed springs with which the arm successively coacts, the springs constituting a resilient buffeting mechanism for the rotatable member; a resilient telescoping structure pivotally assembled with the rotatable member and constituting means for holding the engaging elements in coacting relation; and means for pivotally supporting the telescoping structure, substantially as described. 115

5. In a device of the class described, a pair of intersecting tracks comprising rails; a base located at the angle defined by the rails; a rotatable member journaled on the base; a rail section carried by the rotatable 125 member and adapted to be alined with the respective rails when the rotatable member is operated; operating means for rotating the rotatable member; an arm projecting from the rotatable member; and opposed 130

- 5 springs with which the arm successively contacts, the springs constituting a resilient buffering mechanism for the rotatable member; a resilient telescoping structure pivotally assembled with the rotatable member and constituting means for holding the engaging elements in coacting relation; and means for pivotally supporting the telescoping structure, substantially as described.
- 10 6. In a device of the class described, a pair of intersecting tracks comprising rails; a base located at the angle defined by the rails; a rotatable member journaled on the base; a rail section carried by the rotatable member and adapted to be alined with the respective rails when the rotatable member is operated; operating means for rotating the rotatable member; an arm projecting from the rotatable member; and opposed
- 15 springs with which the arm successively contacts, the springs constituting a resilient buffering mechanism for the rotatable member; a resilient telescoping structure pivotally assembled with the rotatable member and constituting means for holding the engaging elements in coacting relation; and means for pivotally supporting the telescoping structure, substantially as described.
- 20 7. In a device of the class described, a pair of intersecting tracks comprising rails; a rotatable member journaled at the angle defined by the rails; a rail section carried by the rotatable member and adapted to be
- 25

30 alined with the respective rails when the rotatable member is operated; a three armed lever; a fulcrum therefor; a flexible element connecting one arm of the lever with the rotatable member; a spring connected with another arm of the lever; means for anchoring the springs; a connection united with the third arm of the lever; and wheel operated means located adjacent one rail and operatively united with the connection, substantially as described.

40 8. In a device of the class described, a pair of intersecting tracks comprising rails; a rotatable member journaled at the angle defined by the rails; a rail section carried by the rotatable member and adapted to be 45 alined with the respective rails when the rotatable member is operated; a shaft journaled transversely of one rail and provided with one stationary crank arm and with one adjustable crank arm; means for connecting the stationary crank arm with the rotatable member; a lever extending along one rail, on the inside of the track, and operated by the flange of a wheel of a railway vehicle; a fulcrum for the lever; and means 50 for operatively connecting the lever with the adjustable crank arm, substantially as 55 described.

JOHN W. MATTHEWS.
